UNITED STATES PATENT OFFICE

ANDRÉ SAMUELS, OF LYON, FRANCE, ASSIGNOR, BY MESNE ASSIGNMENTS, TO SAMUELS PROCESS CORPORATION, OF BOSTON, MASSACHUSETTS, A CORPORATION OF MASSACHUSETTS

MACHINE FOR DRYING SHEET MATERIAL

Application filed November 2, 1928. Serial No. 316,782.

This invention relates to a machine for drying sheet material, such as fabric (textile or felted), paper or the like which has, for example, been printed or placed upon a table 5 and glued thereon.

The drying of dressed or other fabrics, for example, has been ordinarily effected by means of a movable framework carrying a fire of wood, charcoal, gas or the like, or 10 the fire is fixed and the fabric is movable. In both cases the fire is arranged below the fabric to be dried. In recent years there has also been devised an electrical apparatus 15 embodying reflectors with heating units therein which reflectors have been carried along and over a printing table as is shown in the U. S. patent to Léculier No. 1,571,282.

The device of this invention depends for its operation upon applying to the sheet 20 material a current of heated air as distinguished from simply radiated heat, as is the case with the apparatus shown in the Léculier patent.

In the drawings:

25 Fig. 1 is a perspective view showing the preferred type of machine in place upon a printing table;

Fig. 2 is a plan view of the same, and

Fig. 3 is a vertical half end elevation.

30 Referring to the drawings, the apparatus in its essentials consists of a carriage A running on a track 2, and carrying an air heating drum R which provides heated air for a blower B operated by an electric motor M.

35 The air heating unit R may warm the air, for example, by means of gas, gasoline or other combustible, though in this particular device it is accomplished by means of electric resistance units 5 which heat the air.

40 supply for the blower. The flow of air is indicated by the arrows f. The air first enters through the apertures c adjacent the heating units 5 and the heated air is drawn from the air heating drum R axially of and

45 towards the blower B and thence downwardly and towards the table 3 upon which the fabric is placed. The quantity of air projected from the blower is controlled by means of a variable shutter device k, l, m

50 registering with the apertures e, e, e, which

damper is controlled by means of the rack m and pinion P connected to and controlled by the handle P' as shown in the drawing. The above described portions of the apparatus are suitably held in the carriage A 55 mounted on rollers A' so that it may be moved along the sides of the printing table. This drive may be effected, for example, by means of an electric motor M² driving, through speed reducing gears (not shown) 60 and the shaft 6, the gears 8 which mesh with racks 10 on the opposite sides of the table as shown in Fig. 2, the speed of advance of the machine being controlled by means of the rheostat r. Thus, in order to dry a given strip of fabric which has been freshly printed or which may have been fastened to the table by means of a liquid adhesive, the heating resistances 5 in the air heating unit R are turned on so as to heat the air and the 65 machine is then started in motion along the table so that heated air is blown down upon the same through the funnel E and shutter, as above described. The current for the motors and resistance units may be 70 supplied through conductors 4 along which ride the contact brushes I.

Having described my invention, what I wish to claim and secure by Letters Patent is:

1. In an apparatus for drying sheet material comprising a movable frame adapted to be moved along a printing table, an air heating unit including a casing, a blower and means for driving the said blower, and a conduit extending from said casing, about said blower to a point of proximity to said table, and a damper between said blower and said table.

2. In an apparatus for drying sheet material upon a printing table a carriage adapted to be moved along said table, an air heating unit and blower attached to said carriage, means to drive said blower, means encasing said unit and blower to conduct heated air 90 downwardly and upon the material to be dried, and valve means controlling said air conducting means.

3. In an apparatus for drying sheet material upon a printing table a carriage adapted 100

to be moved along said table, an electric air heating unit and blower attached to said carriage, means to drive said blower, means enclosing said unit and blower to conduct heated air downwardly and upon the material to be dried, and valve means controlling said air conducting means.

4. In an apparatus for drying sheet material upon a printing table, a housing comprising an air heating drum at one end thereof, a damper controlled nozzle at the other end thereof and a conduit connecting said drum and said nozzle, a blower located in said conduit between the drum and the nozzle, means to drive said blower, said housing and associated elements being mounted upon a carriage, and means to move said carriage along said table.

5. In an apparatus for drying sheet material upon a printing table, a housing comprising an air heating drum at one end thereof having electric resistances circumferentially spaced about the interior and air inlet ports formed adjacent said resistances, a damper controlled nozzle at the other end thereof and a conduit connecting said drum and said nozzle, a blower located in said conduit between the drum and the nozzle, means to drive said blower, said housing and associated elements being mounted upon a carriage, and means to move said carriage along said table.

6. In an apparatus for drying sheet material upon a printing table, a housing comprising an air heating drum at one end thereof, a damper controlled nozzle at the other end thereof and a conduit connecting said drum and said nozzle, a blower located in said conduit between the drum and the nozzle, means to drive said blower, said housing and associated elements being mounted upon a carriage, means to move said carriage along said table, and means mounted on said table to supply current to said blower and carriage operating means.

7. In an apparatus for drying sheet material upon a printing table, a housing comprising an air heating drum at one end thereof having electric resistances circumferentially spaced about the interior and air inlet ports formed adjacent said resistances, a damper controlled nozzle at the other end thereof and a conduit connecting said drum and said nozzle, a blower located in said conduit between the drum and the nozzle, means to drive said blower, said housing and associated elements being mounted upon a carriage, means to move said carriage along said table, means mounted on said table to supply current to said blower and carriage operating means and said electric resistances.

8. In an apparatus for drying sheet material upon a printing table, a housing enclosing a source of heated air and means to supply heated air to the table, and means to pass

said heated air from the housing to the first mentioned means, and means to movably mount said housing and enclosed elements on said table.

9. In an apparatus for drying sheet material upon a printing table, a housing enclosing a source of heated air comprising a series of electric heating units and enclosing a means to supply heated air to said table comprising a movable damper and an opening in said housing and enclosing means to pass said heated air from the housing to the first mentioned means comprising a blower located between said housing and said first mentioned means, and means to movably mount said housing and associated elements on said table.
